(57) **CLAIM**

The ornamental design for a basketball goal assembly, as shown and described.

DESCRIPTION

FIG. 1 is a perspective view of a basketball goal assembly showing our new claimed design in an environment of use; FIG. 2 is a front elevational view of the basketball goal assembly; FIG. 3 is a back elevational view thereof; FIG. 4 is a right-side elevational view thereof; FIG. 5 is a left-side elevational view thereof; FIG. 6 is a bottom plan view thereof; and, FIG. 7 is a top plan view thereof.

The broken lines in FIG. 1 depict environmental subject matter and form no part of the claimed design. The broken lines in FIGS. 2-7 depict portions of the article that form no part of the claimed design.

1 Claim, 7 Drawing Sheets
